UNITED STATES PATENT OFFICE.

LLOYD A. FELL, OF WARREN, OHIO.

APPARATUS FOR PRODUCING VACUUMS IN ELECTRIC LAMPS.

1,086,759.

Specification of Letters Patent.

Patented Feb. 10, 1914.

Application filed January 2, 1913. Serial No. 739,812.

To all whom it may concern:

Be it known that I, LLOYD A. FELL, a citizen of the United States of America, residing at Warren, in the county of Trumbull and State of Ohio, have invented certain new and useful Improvements in Apparatus for Producing Vacuums in Electric Lamps, of which the following is a specification.

This invention relates to apparatus for producing vacuums in electric lamp bulbs and the like, in which powdered phosphorus, phosphoric anhydrid, or other moisture absorbing material is used; and the object of my invention is to prevent the entrance of said material into the bulbs of unfinished lamps in case of accident, as hereinafter explained, and thereby to prevent the destruction of partially exhausted and uncompleted lamps and consequent financial manufacturing loss. I attain that object by mechanisms of which the accompanying drawings illustrate the most simple and my preferred form.

Figure 1 is a front elevation, partly in section, of an exhausting apparatus embodying my improvement; Fig. 2 is a view of one form of my improvement unassembled and Fig. 3 is a section taken on the line A—A of Fig. 2.

Similar numerals refer to similar parts throughout the several views.

In the manufacturing of incandescent lamps the final operation after the filaments have been seated in the bulbs, consists in exhausting the air from the bulbs and thereupon sealing off or closing the extreme outer end of the bulb by melting the stem in which the bulb terminates so that it will drop off and close up the bulb by the formation of a tip thereon. For economy of time and labor a plurality of lamps finished to said stage are attached at their stems 2, 2, to tubes 3, 3, ordinarily of brass, by means of retaining tubes 4, 4, of rubber or the like. The tubes 3, 3, are fastened rigidly to a horizontal tube 5 and open thereinto. A tube 6 having a plurality of openings, 7, 7, in its top, is filled with phosphorus or an equivalent substance to absorb moisture, and

is placed inside of tube 5, whose ends are thereupon plugged up as with stoppers 8, 8. Leading from the bottom of tube 5 to exhaust pumps (not shown) are tubes 9, which is called the "preliminary exhaust," and 55 which carries away the bulk of the air in the

bulb bulbs and all loose particles, and 10, which is called the "final exhaust." The exhaust tubes 9 and 10 are alternately manipulated by a pair of gate valves (not shown in detail) which may be operated by 60 a connecting rod 11 and a hand lever 12.

The whole contrivance described is called a "manifold" and for the purposes of this application will be referred to as manifold 35.

A series of nearly finished lamps 1, 1, having been attached at their stems 2, 2, to the manifold 35 it is the duty of the operator, a glass blower, to cut off the stems and seal up the bulbs by forming tips thereon. In doing so not infrequently the stem breaks and an influx of air is admitted not only to the bulb sealing but also to the tube 3 to which that stem was attached; thence the air rushes with great force into and 70 throughout the whole of the manifold, taking up the powdered phosphorus in tube 6, through openings 7, 7, and forcing it up through the other tubes 3, 3, into the rest of the bulbs, 1, 1, where it covers the insides 75 of said bulbs, and frequently the filaments therein; all of which are ruined for commercial purposes thereby and a complete loss of the unfinished lamps is occasioned. As a remedy and preventive I have invented 80 an improvement consisting of the insertion of check valves in the tubes 3, 3, of the manifold 35. I provide valves that will normally permit of the suction of the air from the bulbs 1, 1, through their stems 2, 2 by means of the exhaust pump, and will 85 close said stems or prevent admission of air therethrough into the bulbs in case of accident, in one form of which, illustrated, I insert in each of the tubes 3, 3, a loose 90 inner tube 14, having at one end an annular, open head 15 whose exterior diameter is not greater than that of tubes 3, 3, and having at its other end a cylindrical stem, 16, of reduced diameter and made to fit closely 95 into a corresponding bore 17, through an independent tubular member, 18, having a chamfered end 19 with an opening 20 therethrough, Fig. 2.

A loose plunger 21 is provided having a stem 22 and a conoidal head 23 greater in extreme diameter than said stem. The bore 17 in the member 18 is made large enough to admit the head 23 at one end and smaller at the other end and only large enough to 105 110

loosely receive the stem 22. The bore through the stem 16 is reamed to form a seat 24 for the head 23 of the plunger 22.

The purpose of chamfering the end 19 of 5 the member 18 and of providing the opening 20 therethrough is to permit of the passage of air from the interior of the bulbs to the exhausts during normal workings of the exhaust apparatus.

10 When the operator breaks a bulb stem while sealing it off the pressure of the atmosphere forces the plunger 20 upward so that its head 23 enters the seat 24, closes the valve and prevents the flow of the phosphorus into the other lamps positioned on the manifold.

I claim:

1. In an apparatus of the character described, a lamp-supporting tube, a tube 20 adapted to extend within said first-named tube and headed at its upper end to seat thereon, a tubular member in the lower end of said lamp-supporting tube and into which the lower end of said inner tube extends, and 25 a valve having a stem extending through

said tubular member and a head adapted to seat against the lower end of said inner tube.

2. In an apparatus of the character described, a lamp-supporting tube, a tube 30 adapted to extend within said first-named tube and having its upper end formed with an enlarged head adapted to rest on the end thereof, and its lower end chamfered to form a valve seat, a tubular member seated in the lower end of said lamp-supporting tube and into which the chamfered end of said inner tube extends, a valve having a stem extending through said tubular member and a conoidal head adapted to seat 35 against the lower end of said inner tube, and retaining bands encircling said outer tubes and the lamp to confine the latter therein.

In testimony whereof I affix my signature in presence of two witnesses.

LLOYD A. FELL.
